CLAIM

The ornamental design for a case for electronic communications device, as shown and described.

DESCRIPTION

FIG. 1 is a front perspective view of a case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of the case for electronic communications device showing the lower portion of the case in an open position; and,

FIG. 10 is a rear perspective view of the case for electronic communications device showing the lower portion of the case in the open position.

The broken lines throughout the drawing disclosure depict portions of the case that form no part of the claimed design. The broken lines and regions bounded by broken lines form no part of the claimed design.
